(57) **CLAIM**

The ornamental design for a portable power station as shown and described.

DESCRIPTION

FIG. 1 is a front elevational view of a portable power station showing my new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a top, front and left side perspective view thereof;

FIG. 8 is a top, rear and left side perspective view thereof;

FIG. 9 is an enlarged view of portion 9 in FIG. 7;

FIG. 10 is an enlarged view of portion 10 in FIG. 7; and,

FIG. 11 is an enlarged view of portion 11 in FIG. 8.

The broken lines in the drawings illustrate portions of the portable power station which form no part of the claimed design.

The dot-dash broken lines define the bounds of the claimed design and form no part thereof.
